UNITED STATES PATENT OFFICE

2,483,001

METHOD OF MAKING ARCH-TYPE CONDUITS

Firman L. Carswell and Otto W. Schmidt,
Kansas City, Mo.

Application March 4, 1946, Serial No. 651,805

8 Claims. (Cl. 153—10)

1

This invention relates to the method of making arch-type culverts and has particular reference to circumferentially, corrugated, metal arch-type conduits.

The principal object of the present invention is the method of forming an arch-type culvert by applying pressure to the inside walls of a cylindrical metal tube whereby it is distorted to present an arch-type conduit.

Another object of this invention is the provision of a method of forming arch-type culverts by applying internal pressure to the inside wall of a cylindrical metal tube in substantially opposite diametrically disposed points whereby the tube is transversely elongated on its horizontal axial plane and shortened on its vertical diameter to form an arch-type conduit.

A further object of the invention is the provision of a method for making arch-type conduits which comprises first forming a substantially cylindrically, corrugated, metal tube, positioning a pair of movable convex forms inside said tube and applying pressure to said forms whereby they are caused to move in substantially opposite directions against the wall of said tube whereby the tube is elongated transversely along its horizontal diameter and simultaneously shortened along its vertical diameter, and limiting the downward movement of the upper arch of said tube as the lower portion of the tube is tensioned to form a relatively flat bottom.

Other objects are simplicity and economy of carrying out the method, efficiency and accuracy of the method, and adaptability for use in the formation of non-curved, non-circular culverts of various cross sections.

With these objects in view, as well as other objects which will appear during the course of the specification wherein reference is had to means for carrying out the methods which are shown in the drawings wherein:

Figure 1 is an end elevation of the apparatus with the forms retracted to receive a substantially circular tube thereabout as shown.

Fig. 2 is a plan view of the apparatus with the forms extended and the corrugated tube shown in section.

Fig. 3 is a sectional view taken on line III—III of Figure 2.

Fig. 4 is a reduced side elevational view of the

2

apparatus with a tube shown in the suspended position ready for forming.

Fig. 5 is a sectional view of the apparatus taken on irregular line V—V of Figure 3.

Fig. 6 is a diagrammatic view showing the feed and exhaust pipes to and from the hydraulic rams.

Throughout the several views like reference characters refer to similar parts and the numeral 10 designates a frame having a base 12 on which is mounted a standard 14 adjacent its one end. A horizontally disposed composite beam 16 is supported on top of said standard to extend the full length of the base and is secured at its end adjacent said standard by means of downwardly diverging bars 17 which respectively engage the outer extremities of the base. The main body of the beam 16 extends above base 12, is substantially parallel with, and is adapted to receive a tubular member thereabout for forming.

Beam 16 is preferably made up of a heavy I-beam 18 provided with a lighter I-beam 20 which has its lower flange 22 securely attached to the upper flange of I-beam 18. Securely welded to the lower flange of beam 18 is a series of bars 19 which serve as tracks and extend at right angles to the beam. Similar series are positioned on opposite sides of the beam and are adapted to receive rollers for support-moving forms by means of which the cylindrical tube is formed.

Series of forms 24 and 26 are disposed on opposite sides respectively of said beam 18 and each form comprises a pair of transversely disposed parallel members 28 joined together by channel irons 30, angle irons 32 and arcuate plate 34. The outer edge of each of the members 28 is shaped to conform to the inner contour of the conduit when it is fully extended by the power applied to the forms. It will be noted that the channel irons, angle irons and arcuate plates 30 joining these parallel members together are disposed in parallel relation to the I-beam 18 and have their outer faces flush with the outer edges of the parallel members 28, thus serving to contact the inner corrugations 92 of the circumferentially corrugated tube during the forming operation.

Instead of using spaced apart connecting members, continuous plates might be used to bear against the inner wall of the corrugated tube.

The lower portion of members 28 each have an ear 36 carrying stud 38 on which is mounted a roller 40 which rests on one of the tracks 19. The upper free ends of members 28 have slots 42 which are disposed in parallel relation with the track bars 19 so that the form is adapted to move at substantially right angles to the beam and in a horizontal plane.

The length of the forms 24 may vary, furthermore, the number of forms of each side of the beam may be such as to make it possible to simultaneously form a conduit of any desired length. In the drawings we have shown but two forms on each side; each form is powered by two hydraulic jacks 44 which are respectively positioned adjacent opposite ends of the form with their cylinder portions 46 pivoted at 49 to transverse ribs 48 positioned between the upper and lower flanges of I-beam 18 and with its piston rod 51 pivoted at 53 to a pair of plates 50 secured to spaced apart angle irons 32 and arcuate plate 34. These jacks are so mounted that they are substantially parallel with the tracks 19 and are pivoted at their opposite ends to permit slight up and down movement of the form relative to the frame during the forming operation.

Referring to Figure 2, it will be noted that the members 28 of forms 24 and 26 overlap and are slidably secured together by pins 52 passing through slots 42 and which are anchored to ears 54 formed integral with beam 20. For rigidly supporting the upper portion of the forms the members are adapted to rest upon the upper flange of beam 20 as shown.

The forms 24 and 26 are each provided with a tension spring 56 attached at 58 to the outer portion of the form and at 60 to the beam 18, and are so tensioned that when the pressure is released in the jacks they will function to exhaust the jack cylinders and move the forms back to the normal position, shown in Figure 1, for receiving a tube for forming.

Referring to Figure 1 it will be noted that a channel member 94 is positioned on top of the beam 20 and cooperates with the forms 24 and 26 to maintain the upper portions of the conduit in an arched form. The lower portions of the form are spaced apart a relatively great distance whereby that portion of the tube being formed is tensioned and pulled to a relatively flat form to form the bottom of the conduit.

The jacks are operated by fluid pressure as shown in Figure 6. A pressure feed pipe 62 leads from any suitable fluid pressure means and is controlled by three-way valves 64 and 66 which regulate the flow of the fluid pressure to and from the jack cylinders 44. Pipes 68, 70 and 72 connect feed pipe 62 with the four jacks which operate the first pair of forms 24 and 26, and pipes 74, 76 and 78 connect the feed pipe to the four jacks which operate the second set of forms 24 and 26. Valves 64 and 66 are independently operable so that two or all the forms may be simultaneously operated. As indicated, the valves are set to feed pressure fluid to the jack cylinders. By throwing the valve levers 80 the feed pipe will be closed to the cylinders and the exhaust pipe 82 will be connected with all the cylinders so that the springs 56 will be permitted to contract to force the fluid from the cylinders and retract the forms 24 and 26. It is quite apparent that any desired number of sets of forms might be operated in this manner to form conduits of any desired lengths.

Referring to Figure 4 it will be noted that the

corrugated tube T is suspended by two slings 84 which engage hooks 86 suspended from a wheeled carriage 88 longitudinally adjustable on track 90. This carriage support permits the easy movement of the tube to the proper position over the forms. These slings may be left in position during the forming operation and after the forms are retracted the conduit will take a form due to the release of the form pressure so that it can be supported by said slings and removed from the apparatus while suspended on the track.

During the conduit forming operation it will be observed that inner corrugations 92 rest against the forms to insure the proper arching of the tube, also the channel irons 94 secured on the top flange of beam 20 on the vertical, central line of the tube is of a proper predetermined height to limit the downward movement of the arch during the forming operation. To strengthen the conduit, the sharp curves at the opposite sides of the conduit are provided. These sharp curves also make it possible to provide a wide base for the conduit to carry a large volume of water adjacent the bottom of the conduit.

The forms 24 and 26 are so constructed that they function to contact and curve the major upper portion of the pipe, and are spaced apart at their lower portions a relatively great distance so that that portion of the tube therebetween is put under tension and pulled to a relatively flat form to produce a substantially flat bottom for the conduit.

The application of pressure to the inside of the corrugated tube may be varied from the structure shown and described without departing from the spirit of the invention and hence we do not wish to limit ourselves to the exact construction herein set forth.

What is claimed as new and desired to be protected by Letters Patent is:

1. The method of making a corrugated arch-type culvert which comprises first forming a substantially cylindrically shaped, circumferentially corrugated, metal tube, applying pressure in a plane parallel to and spaced from the axis of said tube to the inner wall of said tube to broaden the arch of the portion of said tube opposite said force plane and to tension the portion of said tube adjacent said force plane whereby it is formed to produce a relatively flat portion.

2. The method of making a corrugated, arch-type culvert which comprises first forming a substantially cylindrically shaped, circumferentially corrugated, metal tube, applying pressure to the inner wall of said tube in a plane parallel to and beneath the axis of said tube to force the upper portion of the tube into an arcuate shape of relatively small radius and simultaneously to flatten the lower portion of the tube wall to produce a relatively flat bottom section of greater radius.

3. The method of making a corrugated arch-type conduit comprising applying pressure to the opposite inner walls of a substantially cylindrical, corrugated tube in a plane parallel to and spaced below the axis of said tube whereby it is transversely elongated along its major horizontal plane and foreshortened at its vertical central plane to form a conduit having a relatively sharply arched upper portion and a relatively flat arched bottom portion.

4. The method of making an arch-type culvert which comprises first applying an internal expanding pressure to a cylindrical metal tube in a plane parallel to but spaced below the hori-

zontal axial plane of said tube whereby the cross-section of said tube is lengthened horizontally and shortened vertically and applying an internal pressure to said tube transversely to the plane of said expanding pressure and at the upper portion of said tube to limit the inward movement of said upper tube portion, whereby a culvert is produced having a relatively sharply arched top portion and a relatively flat arched bottom portion.

5. The method of producing a tube having in cross-section an arched portion and a relatively flat connecting portion between the ends of said arched portion, comprising exerting an expanding pressure against substantially opposite internal walls of a deformable cylindrical tube along generating lines of said tube lying in a plane spaced apart from the axis of said tube in the direction of said relatively flat connecting portion.

6. The method of making an arch-type tube from a cylindrical metal tube comprising applying an outward force against the opposite inner walls of said tube along lines lying in a single plane parallel with and spaced apart from the axis of said tube to deform the portions of said tube at opposite sides of said face plane in unequal degrees.

7. The method of making an arch type tube from a cylindrical tube comprising applying an outward force against the opposite inner walls of said tube along generating lines of said tube lying in a single plane parallel to and spaced apart from the axis of said tube, to deform said tube to present a relatively flat section along 30 one side thereof.

8. The method of making an arch-type tube comprising applying internal pressure to substantially opposite sides of a cylindrical tube in a single plane only, said plane being spaced slightly below a horizontal axial plane of said tube to form an arch-type culvert whereby the tube portion below and between the lines of application of said pressure is tensioned to form a relatively flat section in said tube.
